ARC LAMP REGULATING CIRCUIT

Maxey A. Hankins, Los Angeles, Calif., assignor,
by mesne assignments, to Mole-Richardson Co.,
Los Angeles, Calif., a corporation of California

Application March 17, 1947, Serial No. 735,157

6 Claims. (CL 315—58)

1

My invention relates to arc lamp control circuits for stabilizing the light output of an illuminating arc.

In the operation of arc lamps, the most desirable characteristic to be maintained is uniformity of quality and quantity of light produced by the lamp. For example, in the illumination of motion picture sets, the most desirable characteristic is that of maintaining uniformity of quality and quantity of illumination so as to maintain the exposure density of the film at a relatively constant value.

Arc lamps that are generally used for illuminating purposes employ a machine for feeding carbon or other electrodes toward the arc as the ends of these electrodes are consumed by the arc. Accordingly, stationary brushes are disposed within the arc machine for supplying electric current to the electrodes regardless of the amount of movement of the electrodes. Generally two or more brushes are required for each electrode to obtain the desired current-carrying capacities. In spite of the fact that a ballast resistor is used with arc lamps, there are variations in the arc current resulting in the undesired variations in the quantity and quality of light. I have discovered that these variations in illuminating characteristics are associated with variations of current in the brush circuits.

I have discovered further that the illumination of an arc may be effectively regulated by the insertion of resistors in the brush circuits of the arc electrodes. This control of the arc is much more effective than by the use of a ballast resistor alone, and is attributable to the fact that variations in resistance of the several brush circuits result in variations of current through the several brushes which have an adverse effect upon the arc even though the overall arc current may remain substantially uniform.

It is therefore a general object of my invention to provide an improved illuminating arc.

Still another object of my invention is to provide an arc control circuit wherein a plurality of brushes supply current to each electrode, and the current through each brush is controlled by an impedance.

Another object of my invention is to provide an illuminating arc circuit wherein brush resistors may supplement or supplant the normal ballast resistor generally used in arc circuits.

Other objects and advantages of my invention will be apparent in the following description and claims, considered together with the accompanying drawings, in which

2

Fig. 1 is a schematic arc circuit wherein one of the arc electrodes is supplied with current through a plurality of brushes connected to fixed resistors; and

5 Fig. 2 is a schematic arc circuit wherein current is supplied to one of the arc electrodes through a plurality of brushes, the current of which may be controlled by variable resistors.

Referring to Fig. 1, two carbon rods 10 and 11 may form the negative and positive electrodes, respectively, between which may be struck an arc 12 which may be used for any desired purpose such as illumination. The negative electrode 10 may be connected by a conductor 13 to any 10 suitable source of supply represented schematically as a battery 14, although it will be appreciated that any other type of power source could be utilized, such as an electric generator. The positive electrode 11 may be supplied with current through a plurality of brushes 16 maintained generally stationary within an arc machine, as is well known in the art. These brushes may be resiliently urged toward the electrode 11 by any suitable means (not shown) such as a spring so that a good electrical contact will be maintained with the electrode. Current may be supplied to the brushes 16 by a conductor 17 connected to the opposite terminal of the power supply 14, and the conductor 17 may have two 15 branches 17a and 17b leading to the two brushes 16. Each brush circuit may include a resistor 18 provided especially in accordance with the invention, and the resistors may be connected by conductors 19 to their respective brushes.

20 30 35 In the operation of the circuit of Fig. 1 an arc may be struck between the electrodes 10 and 11 in any suitable manner, and thereafter will maintain itself. The current to the positive electrode 11 will tend to divide itself between the two brushes 16 and thus produce approximately equal

30 35 40 45 voltage drops across the resistors 18 which may be used as ballast resistors if desired. It will be appreciated, however, that minute differences of resistance between the two brush circuits may result in an increase in current of one brush circuit over the other. For example, the sliding of the electrode 11 past the brushes 16 will produce variations from time to time in the contact resistance between the brushes and the electrode.

40 45 50 55 Accordingly the brush having the least contact resistance will tend to draw the heaviest current.

I have found that variations in the current through the brushes have a pronounced effect upon the illumination of the arc. This may be due to the fact that since the brushes are gen-

erally disposed closely adjacent to the end of the electrode, the magnetic field produced by the current passing through the brushes may extend to the area of the arc. Therefore when the brush currents are unequal so that the magnetic field of one does not balance the magnetic field of the other, the magnetic field of the brush carrying the most current predominates and accordingly deflects the arc to some extent, changing its illumination characteristics. The insertion of the resistors 18 in accordance with my invention, however, eliminates this influence due to variations in brush current by maintaining the brush currents approximately equal at all times. Accordingly the resistors 18 should be of equal ohmic resistance for brushes of similar size. By making the resistance of the resistors 18 large compared to the contact resistance of the brushes, a change of brush contact resistance will not appreciably affect the resistance in the circuit of that brush, thus maintaining the brush current substantially constant. Thus the resistors 18 automatically regulate the current flowing through the respective brushes by providing a substantially equal current in these brush circuits.

Shown in Fig. 2 is a modified form of apparatus embodying my invention wherein the resistors are disposed in the brush circuit of the negative electrode, and further, the resistors are variable so as to obtain any relative amounts of current in the brushes. Accordingly an arc 21 may be struck between a positive electrode 22 and a negative electrode 23. The positive electrode 22 may be connected by a conductor 24 and a ballast resistor 26 to a suitable source of supply, such as a battery 27. A conductor 28 may be connected to the other terminal of the power supply and may have three branches 28a, 28b, and 28c connected, respectively, to three variable resistors 29. The other ends of the resistors 29 may be connected through conductors 31 to brushes 33 contacting the negative electrode 23.

In operation, the arc 21 may be struck in any suitable manner and will thereafter maintain itself. The arc current distribution in the brush circuits to the electrodes may be precisely regulated by means of the resistors 29 disposed in the brush circuits particularly in accordance with the invention. The brushes 33 are preferably symmetrically arranged about the electrode 23 when the resistors 29 are maintained at equal ohmic settings. If, however, there is an asymmetric arrangement of brushes 33, or if the positive electrode 22 is disposed at an angle with respect to the negative electrode 23, or for any other reason there is some asymmetrical aspect to the arc as a whole, the current through the various brushes may be precisely regulated by means of the variable resistors 29. The resistors 29 act in the same manner as the resistors 18 of Fig. 1 to give a substantially constant drop in each brush circuit, despite the fact that there might be variations in the contact resistance of the brushes. Thus the magnetic fields generated by the currents passing through the various brushes may be precisely controlled, and the illumination of the arc accordingly may be carefully controlled.

From the combined illustration of Figs. 1 and 2 it is obvious that my invention may be applied either to the positive electrode or to the negative electrode, or to both. Further, it is obvious that

the invention may be employed either with or without a ballast resistor for the arc. Further, the resistors may be variable in any type of circuit or combination. The only essential element is that there be a plurality of brushes for one or more electrodes, and that a current-controlling element be disposed in one or more of these brush circuits to regulate the relative currents between them.

10 It will be obvious to those skilled in the art that various types of impedance devices may be employed other than resistors. For example, inductors or coils could be employed in place of the resistors to effectively choke down any increase of direct current and to supply direct current when the current through the particular brush circuit momentarily drops. Also, in the case of alternating current arcs, capacitors could be effectively utilized for the same purpose as the resistors illustrated.

15 From the foregoing it is obvious that various modifications and equivalents could be utilized without departing from the true spirit and scope of my invention. Accordingly I do not limit myself to the precise disclosure, nor otherwise, except by the terms of the following claims:

I claim:

1. An arc circuit comprising a plurality of arc electrodes, parallel circuits supplying current to at least one of the electrodes, and current regulating devices disposed in each of the parallel circuits.

2. An arc circuit comprising a pair of electrodes, a plurality of wires connected in parallel to at least one of the electrodes, and impedances disposed in each of the parallel wires.

3. An arc circuit comprising a pair of electrodes between which an arc may be struck, a plurality of brushes contacting at least one of the electrodes so that the electrode may be moved relative thereto as it is consumed by the arc, a source of electric current, parallel connections from the source to the brushes, and resistors disposed in the parallel connections.

4. An arc circuit comprising a pair of electrodes, at least two brushes contacting one of the electrodes, a source of current supply, parallel circuits connecting the supply and the brushes, and equal resistors placed in each brush connection so that the current to each brush will be maintained approximately equal.

5. An arc circuit comprising a pair of electrodes between which an arc may be struck, a plurality of brushes contacting at least one of the electrodes so that the electrode may be moved relative thereto as it is consumed by the arc, a source of electric current, parallel connections from the source to the brushes, resistors disposed in the parallel connections, and a ballast resistor connected in series between the supply and one of the electrodes.

6. An arc circuit comprising a pair of electrodes between which an arc may be struck, a plurality of brushes contacting one of the electrodes so that the electrode may be moved toward the arc as the electrode is consumed by the arc, a source of current supply, conductors connecting one terminal of the supply to the brushes in parallel, and variable resistors disposed in each parallel conductor to each brush, so that the current through each brush may be regulated relative to the current in the other brushes.

MAXEY A. HANKINS.
